UNITED STATES PATENT OFFICE.

ASHLEY C. BENNETT, OF MINNEAPOLIS, MINNESOTA.

CARBURETER.

1,130,700.

Specification of Letters Patent. Patented Mar. 9, 1915.

Application filed February 1, 1913. Serial No. 745,631.

To all whom it may concern:

Be it known that I, ASHLEY C. BENNETT, a citizen of the United States, residing at Minneapolis, in the county of Hennepin and State of Minnesota, have invented certain new and useful Improvements in Carbureters, of which the following is a specification.

My invention relates to carbureters, and has for its object to provide a carbureter in which the fuel oil will be delivered into the air passage in extremely thin and widely extended films from a horizontal feed pipe, also to provide means for increasing the velocity of the air under low speeds where said air passes the fuel delivering members.

The full objects and advantages of my invention will appear in connection with the detailed description thereof and are particularly pointed out in the claims.

In the drawings, illustrating the application of my invention in one form. Figure 1 is a section of a portion of a carbureter showing my improvements connected therewith. Fig. 2 is a sectional plan view of the delivery pipe for the fuel mixture and the oil spreading means above referred to. Fig. 3 is a plan view of one of the spreaders employed in connection with my invention. Figs. 4 and 5 are enlarged sectional views showing the spreader members in two different positions.

By means of a casing 10, a fuel oil reservoir or chamber 11 is provided, and separated therefrom is another chamber 12 in which said oil is vaporized and mixed with air. A horizontal pipe 13 has the interior thereof connected with chamber 11 by means of the duct 14, which is controlled by a needle valve 15. Means not shown, of well-known construction, are provided for keeping the fuel oil within the reservoir 11 at a level approximately that of the top of horizontal feed pipe 13. A port 16 is provided for primary air, which is unobstructed and delivers air into the carbureter when the engine is running at slow speeds. A port 17 is also provided for what is known as secondary air and is controlled by valve 18, which admits additional air to the chamber 12 when the engine is run at higher speeds, so that the vacuum produced thereby is increased. The pipe 19, through which the explosive mixture of air and fuel oil vapor is delivered to the engine, is so positioned relative to ports 16 and 17, and the delivery

pipe 13 so positioned across the lower end of pipe 19, that both primary and secondary air will enter pipe 19 when flowing in directions substantially at right angles to pipe 13. Along the upper edge of pipe 13 is formed a series of apertures 20. Strung upon the feed pipe 13 are a series of distributing members or fins 21, each comprising a pair of plates secured together at their bottom edges 22 and 23 and having their circumferential upper edges 25 normally separated a considerable distance, as clearly shown in Figs. 1 and 4. The members 21 are held in position on feed pipe 13 at the backs 26 thereof by solder or other fastening means, so that successive apertures 20 open from the interior of pipe 13 between pairs of plates of the respective members 21.

As above stated, each pair of plates forming the distributing members 21 normally flare outwardly at the circumferential edges 25 thereof, so that when the various sets of distributing members 21 are assembled upon the feed pipe 13, the adjacent plates of successive members will contact at the tops of their edges 25, as clearly shown in Figs. 1 and 4. These plates are so constructed as to spring outwardly as above indicated with a very light spring action, so that a comparatively small amount of force is required to close them into the position shown in Fig. 5. Now, by reference to Fig. 2, it will be noted that when the members 21 are in normal position with the plates thereof fully expanded so that adjacent plates of successive members contact, a very considerable portion of the area of delivery pipe 19 is closed. When, however, the plates of the succeeding distributing members or fins are closed, as shown in Fig. 5, the area through which air can pass along side of said plates is very largely increased. Now, when the engine is operating at slow speed, and therefore drawing air through the primary port 16 in relatively small proportions, the current of air passing between the adjacent parts of members 21 will not have sufficient force materially to close said members. The aggregate air passage past the edges 25 of members 21, will, therefore, be largely restricted so that the velocity of the air actually passing said edges will be increased, although the amount of air going to the engine cylinder will be the same as would be the case if passage through pipe 19 were not so restricted. The velocity of the air at the

point where vaporization takes place has a direct bearing upon the rate and efficiency of vaporization, the greater the velocity the more complete the vaporization. It is, therefore, of great advantage to increase the velocity at the vaporization point, and my improvements herein described do this without, of course, in any respect increasing the amount of air flowing to the engine.

10 As shown in the Figs. 1 and 4, I have arranged the members 21 so that the same are of increasingly greater height from the part of the feed pipe positioned toward the fuel admission to the end of said feed pipe. This 15 will have the effect under moderate drafts of causing the fuel oil to feed principally from the edges of the shorter members while as the draft increases the oil will progressively reach the edges of succeeding members until it reaches the highest thereof.

20 It is to be noted that the members 21, positioned as they are in vertical planes with their closed edges down, in fact comprise open topped cups of greater or less extent 25 according to the angle which the edges 22 and 23 make with one another. Surplus oil feeding from the apertures 20 may and will be retained in these cups. As the speed of 30 the engine increases the oil in the cups may be drawn up into vaporizing position as rapidly as the conditions of feed may require.

I claim:

1. A carbureter comprising a casing forming an air passageway, an oil feed pipe extending horizontally across said air passageway and provided with openings along one side, means to deliver fuel oil into the pipe and to the openings, a series of plates 35 or fins secured along said pipe across the air passageway and extending away from said openings, the adjacent members of said plates being yieldingly flared so as normally 40

to contact and restrict the area of the air 45 passages in the pipe, said flared portions being movable by the current of air passing through the pipe to vary the amount of said flare and increase the area of the air passageways in proportion to the strength of the 50 air current.

2. A carbureter comprising a pipe for delivering fuel mixture, a feed pipe extending horizontally across said delivery pipe and having apertures along the top thereof, means for delivering fuel oil into said feed 55 pipe and to said apertures, a series of double walled spreader members on said feed pipe, each member having a wall thereof on each side of an aperture, said walls being extended upwardly into the delivery pipe away 60 from the feed pipe, and means for conducting a current of air into said delivery pipe from below the feed pipe and flaring members.

3. A carbureter comprising a pipe for delivering fuel mixture, a feed pipe extending horizontally across said delivery pipe and having apertures along the top thereof, means for delivering fuel oil into said feed pipe and to said apertures, a series of double 70 walled spreader members on said feed pipe, each member having a wall thereof on each side of an aperture, said walls being extended upwardly into the delivery pipe away 75 from the feed pipe, and means for conducting a current of air into said delivery pipe from below the feed pipe and flaring members, the walls of said spreader members progressively increasing in height from the 80 inlet end of the feed pipe.

In testimony whereof I affix my signature in presence of two witnesses.

ASHLEY C. BENNETT.
